(57) **CLAIM**

The ornamental design for a base for cosmetic applicators as shown and described.

DESCRIPTION

The file of this patent contains at least one figure executed in color. Copies of this patent with color figures will be provided by the Office upon request and payment of the necessary fee.

FIG. 1 is a front, right, top perspective view of a base for cosmetic applicators showing the new design.

FIG. 2 is a front elevation view of the base for cosmetic applicators of FIG. 1.

FIG. 3 is a rear elevation view of the base for cosmetic applicators of FIG. 1.

FIG. 4 is a left side elevation view of the base for cosmetic applicators of FIG. 1.

FIG. 5 is a right side elevation view of the base for cosmetic applicators of FIG. 1.

FIG. 6 is a top plan view of the base for cosmetic applicators of FIG. 1; and,

FIG. 7 is a bottom plan view of the base for cosmetic applicators of FIG. 1.

The broken lines illustrate portions of the base for cosmetic applicators that form no part of the claimed design.
